UNITED STATES PATENT OFFICE.

ROBERT W. PRESCOTT, OF CLEVELAND, OHIO.

ATOMIZER.

SPECIFICATION forming part of Letters Patent No. 606,240, dated June 28, 1898.

Application filed July 24, 1897. Serial No. 645,758. (No model.)

To all whom it may concern:

Be it known that I, ROBERT W. PRESCOTT, a citizen of the United States, and a resident of Cleveland, county of Cuyahoga, and State 5 of Ohio, have invented a new and useful Improvement in Atomizers, of which the following is a specification, the principle of the invention being herein explained and the best mode in which I have contemplated applying 10 that principle, so as to distinguish it from other inventions.

The annexed drawings and the following description set forth in detail certain mechanism embodying the invention, such disclosed 15 means constituting but one of various mechanical forms in which the principle of the invention may be used.

In said annexed drawings, Figure I represents a longitudinal cross-sectional view of 20 my improved atomizer, showing the piston-rod and piston and the valves in elevation thereon; and Fig. II represents an enlarged central longitudinal section of the nozzle of my said atomizer.

25 The device consists of an inner piston-cylinder A, each end of which projects beyond the end of an outer liquid-chamber B, surrounding the major portion of said piston-chamber. The handle end of the piston-cylinder is provided with suitable packing and gland *a* to suitably pack the piston-rod *a'*. A suitable aperture and cap *b* are provided at one end of the liquid cylinder or chamber for the introduction of the liquid to be atomized. 30 Intermediate of the nozzle and the nozzle end of the liquid-chamber is provided a liquid-inlet tube C, communicating with the inside both of the liquid-chamber and piston-cylinder, whereby the liquid may be introduced 35 from said liquid-chamber into the piston-chamber. The said liquid-inlet is controlled by a suitable valve C', actuated by a spring *c*, which bears against the inner end of a plug *c'*, located in the aperture *c* in the piston-cylinder opposite the valve-seat at the end of 40 the inlet-tube. Intermediate of said valve and the liquid-nozzle is located, in an enlarged portion of the piston-cylinder, a second valve D, actuated by a spring *d*, bearing 45 against the opposite end of said enlarged portion, in a direction opposite that given by the liquid on being forced out from the de-

vice. The nozzle E is formed with a helical outlet *e*, which gives the emerging liquid a gyratory motion.

55 The operation of the device is as follows: The piston-rod and piston being drawn back from a position such as is indicated in the drawings, the external pressure of the atmosphere tightly closes the valve D against the entrance of air into the piston-cylinder. At the same time the air above the inlet-valve is expanded, causing a reduction in the pressure exerted on the upper side of the valve C', whereupon the pressure of the air upon 60 the liquid in the chamber forces a portion through the inlet-tube and into the piston-chamber. On moving the piston sharply in the opposite direction the said liquid is expelled past the valve D, which is opened by 65 the pressure of the air thereby produced in the piston-cylinder and out of the end of the nozzle. The exit of the air and liquid from the helical nozzle causes a comminution of the liquid, the helical path giving the air a 70 greater opportunity to separate the particles, thus performing the function of atomizing the liquid.

75 By constructing the atomizer in the above manner—that is, by leading the inlet-tube on the outside of the liquid-chamber and causing it to communicate with a portion of the piston-chamber projecting from the liquid-chamber—the valve C is also brought outside of the said chamber, whereby it may be easily 80 reached for purposes of repair. It is seen that it is only necessary to remove the plug *c'* to immediately reach the said valve and its seat.

85 Other modes of applying the principle of my invention may be employed instead of the one explained, change being made as regards the mechanism herein disclosed, provided the means covered by any one of the following 90 claims be employed.

95 I therefore particularly point out and distinctly claim as my invention—

1. In an atomizer, the combination of a liquid-chamber, a piston-chamber centrally located within said liquid-chamber and projecting from one end thereof, a suitable piston and piston-rod, a valve-controlled liquid-inlet communicating with said liquid-chamber and the projecting end of said piston-cham-

ber, said projecting end provided with a valve adapted to control atmospheric communication with said piston-chamber and further provided with a suitable atomizing-nozzle, 5 substantially as set forth.

2. In an atomizer, the combination of a liquid-chamber, a piston-chamber centrally located within and projecting from one end of said liquid-chamber, a suitable piston and 10 piston-rod, a valve-controlled liquid-inlet communicating with said liquid-chamber and

the projecting portion of the piston-chamber, said projecting portion provided with a valve adapted to control atmospheric communication with said piston-chamber, the extremity 15 of the latter provided with a helical atomizing-nozzle, substantially as set forth.

Signed by me this 14th day of July, 1897.
ROBT. W. PRESCOTT.
